(57) **CLAIM**

The ornamental design for a charging station for mobile devices, as shown and described.

DESCRIPTION

FIG. 1 is a top, front, left isometric view of a charging station for mobile devices, showing our new design;

FIG. 2 is a bottom, rear, right isometric view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines shown in the drawings represent portions of the charging station for mobile devices that form no part of the claimed design.

1 Claim, 8 Drawing Sheets
